WEB PERFECTING ROTARY PRINTING
PRESSHoward M. Barber, Pawcatuck, Conn., assignor
to C. B. Cottrell & Sons Company, Westerly,
R. I., a corporation of Delaware

Application February 3, 1936, Serial No. 62,072

6 Claims. (Cl. 101—178)

In high speed web perfecting rotary printing presses where quick drying inks and ink drying units are employed in connection with the web printing units, it is most important that the several units be so located with respect to one another as to produce the best possible results with a minimum amount of space and a minimum travel of the web.

This invention comprises, generally, two printing units, two drying units and means for passing the web through said printing and drying units.

This invention more specifically comprises first and second printing units, first and second drying units offset therefrom at right angles thereto and means for passing the web through said printing units in the line of the press and through said drying units laterally with respect to the press.

Practical embodiments of my invention are represented in the accompanying drawings, in which

Fig. 1 represents a diagrammatic top plan view of a double two color press embodying my invention, and means for removing the vapors rising from the heating cylinders of the drying units being omitted;

Fig. 2 represents a diagrammatic longitudinal vertical section, taken in the plane of the line II—II of Fig. 1, looking in the direction of the arrows;

Fig. 3 represents a diagrammatic front end view of the press; and

Fig. 4 represents a diagrammatic cross section, taken in the plane of the line IV—IV of Fig. 1, looking in the direction of the arrows.

The first printing unit is herein shown as adapted to print in two colors, the impression cylinder being denoted by 1, the form cylinders by 2, 3 and the inking mechanisms by 4 and 5 respectively.

The second printing unit is herein shown as also adapted to print in two colors, the impression cylinder being denoted by 6, the form cylinders by 7 and 8 and the inking mechanisms by 9 and 10 respectively.

The first drying unit is herein shown as comprising a large heating cylinder 11 and two small cooling cylinders 12 and 13 respectively. A pipe 14 serves to introduce a heating medium, as steam, into the cylinder 11, and pipes 15 and 16 serve to introduce a cooling medium, as water, into the cylinders 12 and 13 respectively.

The second drying unit is herein shown as comprising a large heating cylinder 17 and two

small cooling cylinders 18 and 19 respectively. A pipe 20 serves to introduce a heating medium, as steam, into the cylinder 17, and pipes 21 and 22 serve to introduce a cooling medium, as water, into the cylinders 18 and 19 respectively. 5

These two drying units are offset from and located at right angles to the printing units.

A turning bar 23 is located in position to direct the web laterally from the first printing unit to the first drying unit, and a second turning bar 10 24 is located in position to direct the web back into alignment with the press before the web is passed to the second or perfecting printing unit.

A turning bar 25 is located in position to direct the web laterally from the second printing unit 15 to the second drying unit, and a second turning bar 26 is located in position to direct the web back into alignment with the press before the web is passed to a predetermined point for future operations.

20 The web may be passed through the press as follows:

The unprinted web passes from the web supply roll 27 around guide rolls 28, 29, 30, 31, 32 to and around the impression cylinder 1 of the first 25 printing unit. From thence the web passes around the turning bar 23 and under the guide roll 33 to and around the heating cylinder 11 of the first drying unit. From thence the web passes around the cooling cylinder 12, guide roll 34, cooling cylinder 13 and guide rolls 35, 36, 37 and 38 to and around the turning bar 24 for bringing the web back into line with the press. The web then passes around the guide roll 39 and compensating roll 40 to and around the impression 30 cylinder 6 of the second or perfecting printing unit, located above the first printing unit. The web then passes over the guide rolls 41, 42 to and around the heating cylinder 17 of the second 35 drying unit. From thence the web passes around the cooling cylinder 18, guide roll 43 and cooling cylinder 19 to and around the guide rolls 44, 45 to the turning bar 26 to again bring the web into line with the press. The web may then be led over the guide roll 46 to a predetermined point 40 for further operations, as cutting, folding, stacking, etc.

Instead of passing the perfected web back into the press from the second drying unit the web may be passed directly from the said drying 50 unit to a predetermined point for further operations as indicated by dot and dash lines in Fig. 4.

The heating cylinders of the two drying units may be provided with suitable means for remov- 55

ing the vapors which arise from the inks as the web passes around said heating cylinders. In the present instance I have shown blowers 47, 48 with their hoods 49, 50 partially enclosing the heating cylinders 11, 17 respectively, and exhaust pipes 51, 52.

It will be understood that the several units may be driven by any well known or approved means, not shown herein, and that the path of the web may be varied to suit different requirements.

It will also be seen that the path of the web is such that the freshly printed side of the web, after it is dried by each drying unit, will not be again subjected to the heat rising from the heating cylinder by said unit.

It will also be seen that I have provided an arrangement of the several units whereby the inks on the freshly printed sides of the web may be thoroughly dried with a minimum travel of the web, the form cylinders and their inking mechanisms of the two printing units being so positioned that ready access thereto is obtained.

It is evident that various changes may be resorted to in the construction, form and arrangement of the several parts without departing from the spirit and scope of my invention, and hence I do not intend to be limited to the particular embodiments herein shown and described.

30   What I claim is:

1. In a web perfecting rotary printing press, first and second printing units in line with the press, two drying units comprising heating and cooling cylinders located out of line with the press, and means for passing the web through said printing and drying units.

2. In a web perfecting rotary printing press, first and second printing units arranged one

above the other in line with the press, two drying units comprising heating and cooling cylinders located out of line with the press, and means for passing the web through said printing and drying units.

3. In a web perfecting rotary printing press, first and second printing units in line with the press, two drying units comprising heating and cooling cylinders located out of line with the press at right angles thereto, and means for passing the web through said printing and drying units.

4. In a web perfecting rotary printing press, first and second printing units arranged one above the other in line with the press, two drying units comprising heating and cooling cylinders located out of line with the press at right angles thereto, and means for passing the web through said printing and drying units.

5. In a web perfecting rotary printing press, first and second printing units in line with the press, two drying units comprising heating and cooling cylinders located out of line with the press at right angles thereto, and means for passing the web through said printing and drying units.

6. In a web perfecting rotary printing press, first and second printing units in line with the press, two drying units comprising heating and cooling cylinders located out of line with the press at right angles thereto, and means for passing the web through said printing and drying units, said means including turning bars around which the web is led on its way to and from the first drying unit.

30   In a web perfecting rotary printing press, first and second printing units in line with the press, two drying units comprising heating and cooling cylinders located out of line with the press at right angles thereto, and means for

passing the web through said printing and drying units, said means including turning bars 35 around which the web is led on its way to and from both drying units.

HOWARD M. BARBER.
